UNITED STATES PATENT OFFICE

ALBERT V. BOETTER, OF CHICAGO, ILLINOIS, ASSIGNOR OF ONE-HALF TO HAROLD P. ULLMAN, OF CHICAGO, ILLINOIS

DESIGN FOR A LAMP

Application filed November 25, 1929. Serial No. 33,546. Term of patent 3½ years.

To all whom it may concern:

Be it known that I, ALBERT V. BOETTER, a citizen of the United States, residing at Chicago, in the county of Cook and State of Illinois, have invented a new, original, and ornamental Design for a Lamp, of which the following is a specification, reference being had to the accompanying drawing, forming part thereof, in which,

The figure is a perspective view of a lamp showing my new design.

I claim:

The ornamental design for a lamp, as shown.

In witness whereof I affix my signature.

ALBERT V. BOETTER.
